UNITED STATES PATENT OFFICE.

GEORG HEINRICH SCHIEFERSTEIN, OF BERLIN-CHARLOTTENBURG, GERMANY.

BELL-RING MACHINERY.

Application filed February 17, 1926, Serial No. 88,942, and in Germany February 26, 1925.

This invention relates to bell-ring-machinery of the type in which the ringing of a bell is caused by a normal rotary motion.

It is one of the objects of my invention to 5 provide a church- or factory-bell with means by which energy may be communicated from a driving mechanism to a bell, without disturbing the natural oscillatory movement of said bell, and in such an amount as to be 10 substantially equal to the damping at normal ringing, but in a greater amount in starting and in ceasing to ring the bell.

Another object of my invention is to time or to tune a driving mechanism with a bell, 15 and loosely to couple mechanically said driving mechanism with said bell.

A further object is to produce a mechanical loose coupling device comprising yielding means, the yieldingness of which causes 20 the stroke of the driving parts to differ strongly from the reciprocating movement of the driven bell-sweep at starting and at ceasing, and rather little at normal ringing the bell.

According to the present invention, a 25 mechanism driven by a rotary prime-mover and producing a reciprocating movement is substantially tuned to the natural frequency of the bell which is to be rung, and is 30 loosely coupled with said bell by means of a peculiar mechanical loose coupling device.

In order that the invention may be clearly understood, reference is hereinafter made to the accompanying drawing, the figure of 35 which is a side view with parts in section of a preferred form of securing my desired result, but I do not mean to limit myself to the exact form shown.

In the embodiment of the invention chosen 40 for illustration and description, and referring to the drawing wherein similar reference numerals designate corresponding parts, the bell 1 suspended on the beam 2 is swingably mounted, and bears sweeps 3, 3 slotted pins 5, 5.

A mechanism comprising in a casing 6 a 45 pulley 7, toothed wheels 8, 8, 8 and cranks 9, 9 is driven by a prime-mover 10 of a normal rotary motion, such as a little electro-motor. A strap 11 may be employed to 50 convey motion from said prime-mover to the pulley's shaft 12. The ratio is determined by the natural period of the bell 1 in such a way that to each full oscillatory motion of the bell substantially corresponds one

revolution of the crank-shafts 13, 13 (which rotate each in inverse direction).

Peculiar mechanical loose coupling devices 14, 14 serve to connect the crank-pins 15, 15 with the pins 5, 5 and to communicate to the bell an amount of energy which is exactly predetermined in a manner hereinafter more specifically described.

The improved coupling device 14 includes 65 a cylindrical casing 16 which is threaded at both ends, caps 17 and 18 respectively are fitted on the opposite ends of the casing and the cap 18 receives in a stuffing-box 19 a tubular rod 20 including one end of a hollow piston-rod 21. The opposite end of the rod 21 is threaded into an aperture 22 for engaging the pin 5.

The piston-rod 21, on which a piston 23 is secured, is perforated and immersed in 75 a fluid 24 of a low freezing point, such as glycerine, with which the cylindrical casing 16 is filled. The tubular rod 20 is provided with a regulating disk 25 by which, when turning the tubular rod, a number of holes 80 of the piston 23 can be closed, the remaining holes are provided with ball-valves 26 opening only when the piston is depressed. The central passage of the piston forms the entrance to the interior of the hollow piston-rod 21, bounded in the top by a plug 27 and serving as an air-chamber 28. Another air-chamber 29 is arranged above the piston in 85 the top of the cylindrical casing 16 in which a tube 30, threaded into the cap 18, forms a 90 chamber of ring-shaped cross-section. Between these two air-chambers the fluid-column 24 in the cylindrical casing 16 is encased.

The two hollow rods 20 and 21 extending 95 through the tube 30 and cap 18 bear adjusting-rings 31 and 32, by which, the turning of the tubular rod 20 on the piston-rod 21, can be effected and the regulating disk 25 can be turned and in this way a number of holes of the piston can be closed or opened without opening the coupling device. By regulating 100 the number of closed holes in this manner the yieldingness of the coupling device and consequently the amount of energy communicated to the bell will be adjusted. This adjustment is so made, that a normal ringing of the bell is caused, whereby the transferred amount of energy automatically is greater at starting and at ceasing to ring 110 the bell.

Another embodiment of my invention dif-

fers from the form illustrated in the drawing, in that the bell is caused to swing by one coupling device only and only one crank in the driving mechanism is provided.

5 Claims:

1. The combination with an oscillating bell and a sweep therefor, of mechanism operating substantially in tune with the natural oscillation frequency of the bell, and 10 means between said mechanism and the bell sweep to vary the power between said mechanism and sweep when the oscillations of the bell deviate from their natural period.
2. The combination with an oscillating bell and a sweep therefor, of mechanism operating substantially in tune with the natural oscillation frequency of the bell, and automatically yielding means between said mechanism and the bell sweep to vary the 15 power between said mechanism and sweep when the oscillations of the bell deviate from their natural period.
3. The combination with an oscillating bell and a sweep therefor; of mechanism operating substantially in tune with the natural oscillation frequency of the bell, and a device between said mechanism and the sweep to vary the power between said mechanism and sweep when the oscillations of 20 the bell deviate from their natural period, comprising a liquid containing cylinder, a piston therein, a hollow piston rod therefor, ports and valves controlling the passage of liquid to opposite sides of the piston, said 25 cylinder containing a body of air above the

liquid therein and said hollow piston rod containing a body of air, whereby the liquid above the piston is virtually acted upon both above and below by the pressure of said air bodies.

4. The combination with an oscillating bell and a sweep therefor, of mechanism operating substantially in tune with the natural oscillation frequency of the bell, and automatically yielding means between said mechanism and the bell sweep to vary the power between said mechanism and sweep when the oscillations of the bell deviate from their natural period, and adjusting devices to adjust the connection between said means and sweep for altering the effective leverage of the sweep.

5. In a bell ringing construction, a bell and its sweep, in combination with a cylinder partly filled with liquid, a piston therein having valves and ports for controlling the passage of liquid to opposite sides of the piston, a hollow air containing piston rod, a tube thereon, a regulating disc on said tube adjusted by said tube from the exterior of the cylinder, means to adjust the connection between the piston rod and sweep to vary the effective leverage of the latter, and mechanism to reciprocate the cylinder substantially in tune with the natural oscillation of a bell, and a prime mover for driving said mechanism.

In testimony whereof I affix my signature.

GEORG HEINRICH SCHIEFERSTEIN.
